LASTING MACHINE

Bernhardt Jorgensen, Marblehead, Mass., assignor to United Shoe Machinery Corporation, Flemington, N. J., a corporation of New Jersey

Original application December 30, 1943, Serial No. 516,253. Divided and this application January 8, 1945, Serial No. 571,747

19 Claims. (Cl. 12—12)

1

This invention relates to lasting machines, the present application being a division of a copending application Serial No. 516,253, filed on December 30, 1943, which matured into United States Letters Patent No. 2,387,331, granted on October 23, 1945. The invention is herein illustrated as embodied in a power-operated machine for lasting the opposite sides of the foreparts of shoes between their toe portions and their waist or shank portions in the manufacture of shoes of a kind in which the margin of the upper in those locations is lasted inwardly over an insole into parallel relation to the bottom of the last and is fastened to the insole by cement. The machine herein shown is in many respects similar to that shown in United States Letters Patent No. 2,346,688, granted on April 18, 1944, on an application of mine, and in some aspects the present invention has in view certain improvements in that machine. It should be understood, however, that the invention is not limited to a machine organization of that particular character, and that in some novel aspects also it is not limited to a machine for lasting the sides of shoes.

The machine herein shown, similarly to that shown in the last-mentioned Letters Patent, is provided with wipers, more broadly definable as overlaying members, which are moved widthwise of the shoe at the sides of the forepart to wipe the margin of the upper inwardly over the insole, and with retarders which are moved outwardly over the insole toward the overlaying members for clamping the margin of the upper against these members to control it in the lasting operation. Early in the lasting operation the retarders are moved reversely in inward directions over the insole by the inward movements of the overlaying members, after which they are moved heightwise of the shoe and outwardly over the overlaying members to release the margin of the upper. Included also in the machine is a shoe rest which is moved heightwise of the shoe into position to support the shoe at the top of the forepart during the operation of the overlaying members and the retarders on the upper.

For purposes of this invention the construction herein shown is such that the shoe rest is moved automatically into its shoe-supporting position at a predetermined time in the operation of the machine by novel means dependent for its operation upon other means whereby the overlaying members and the retarders are operated or controlled. As illustrated, the latter means includes lever mechanism to which movement is

2

imparted through a bodily movable link connection by a fluid-operated piston, and cam means carried by that link connection acts through additional mechanism to impart the required movement to the shoe rest early in the movement of the piston. The cam means is so formed as to maintain the shoe rest thereafter in operative position during further movement of the piston to operate the overlaying members and to control the retarders. It will be evident that this construction is especially advantageous where power for operating the machine is derived from a reciprocating member such, for example, as the above-mentioned piston.

15 For moving the retarders outwardly over the insole in proper time relation to the operative movements of the overlaying members the machine herein shown is further provided, for purposes of this invention, with arms arranged to extend heightwise of the shoe in locations opposite the sides of the shoe and movable by springs about axes extending lengthwise of the shoe under control of the above-mentioned lever mechanism thus to move the retarders, the 20 springs being yieldable to permit the retarders thereafter to be moved inwardly over the insole by the overlaying members. The retarders are directly supported on arms which extend outwardly therefrom widthwise of the shoe, these 25 arms being pivotally mounted on the above-mentioned arms for movements heightwise of the shoe to permit the release of the margin of the upper by the retarders in the manner above described.

30 The above and other features of the invention, including novel means for adjusting the retarders and various novel details of construction and combinations of parts, will now be more particularly described with reference to the accompanying 35 drawings and thereafter pointed out in the claims.

In the drawings,
Fig. 1 is a view partly in right-hand side elevation and partly in vertical section of a machine in which the invention is embodied;

Fig. 2 is a view similar to Fig. 1 of a portion of the structure there shown, but with the parts in different positions;

Fig. 3 is a view mainly in front elevation of 50 the upper portion of the machine, the position of a shoe in the machine being indicated diagrammatically by broken lines;

Fig. 4 is a plan view of the machine, also illustrating the position of a shoe diagrammatically;

Fig. 5 is a view in side elevation of a portion

of the structure shown at the left-hand side of Fig. 4;

Fig. 6 is a plan view similar to a portion of Fig. 4, but showing the parts as they appear when the overlaying members or wipers are at the ends of their inward wiping movements over the shoe;

Fig. 7 is a view of the upper portion of the machine partly in right-hand side elevation and partly in section, with the parts in the same positions as illustrated in Fig. 6; and

Figs. 8, 9, 10 and 11 are views partly in front elevation and partly in section, showing one of the wipers and parts closely associated therewith as they appear at different times in the operation of the machine.

The machine is provided with a column 2 on which is supported a frame 4 having a horizontal top plate 6. Supported indirectly by this top plate, through means presently to be described, is a holdown 8 provided with three presser feet 10 (Figs. 1, 7 and 8) arranged to engage the bottom of the forepart of the insole to determine the position of the shoe heightwise in the machine. As illustrated, two of these presser feet, which engage the insole at considerable distances from the end of the toe, are spaced apart laterally of the shoe, and the third presser foot is arranged to engage the insole in a location nearer the end of the toe. Accordingly, the presser feet are arranged further to determine the position of the shoe with respect to tipping movements about axes extending lengthwise and laterally thereof. The holdown 8 is provided with a stem 12 extending upwardly into a socket formed in a block 14 and engaged at its upper end by a screw 16 in the block to determine adjustably the position of the holdown relatively to the block. A spring 18 in the stem 12 bears at its lower end on a pin 20 which is mounted in the block 14 and extends through a slot in the stem, the spring thus holding the stem at all times up against the screw 16. By adjusting the screw the position of the shoe heightwise may be varied. The block 14 is pivotally mounted on the front end of a substantially horizontal link 22 and also on the front end of a lever 24 substantially parallel to the link 22. The rear end of the link 22 is pivotally mounted on an upwardly extending forked member 26 fast on the frame plate 6, and the lever 24 is also pivotally mounted between its front and rear ends on a pin 28 on this member. The link 22 and the forwardly extending arm of the lever 24 accordingly have the effect of parallel links supporting the block 14 for upward or downward movement without any tipping movement thereof. The rearwardly extending arm of the lever 24 has pivotally mounted on its rear end a depending arm 30 provided with a plate 32 an edge of which is arranged normally to extend over the top of a plate 34 fast on the frame plate 6, so that the arm 30 serves as a latch for positively preventing upward movement of the holdown 8 in response to pressure of the shoe thereon. A spring 36 connected to the arm 30 and to the plate 6 holds the arm normally in operative position. A further purpose served by this latch arm will be hereinafter explained.

The shoe is positioned laterally in the machine by two side gages 38 arranged to engage it at the opposite sides of the forepart, respectively, these gages comprising plates faced with leather or other suitable material and pivotally mounted on vertical pins 40 supported on the front ends

of forwardly and rearwardly extending levers 42. The gages are curved lengthwise of the shoe to approximate the contour of the shoe and by swinging about the pins 40 are permitted to adjust themselves to the shoe. The levers 42 are pivotally mounted between their front and rear ends on vertical studs 44 extending downwardly from the top plate 6, and their rearwardly extending arms are forked to embrace a rod 46 rotatably mounted on the frame. This rod is provided with right and left screw threads 48 in engagement with corresponding threads in blocks 50 against the outer faces of which the forked rear end portions of the levers 42 bear, the blocks being held from turning by contact with the plate 6. A spring 52 connected to fingers 54 on the rear ends of the levers holds the levers constantly against these faces of the blocks. Lengthwise movement of the rod 46 is prevented by two collars 56 and 58 fast on opposite ends thereof and engaging the frame, the collar 56 being knurled for use in turning the rod. It will be understood that by the turning of the rod the blocks 50 are moved equal distances toward or from each other to adjust the side gages 38 for shoes of different widths, the adjustment being preferably such that while the gages determine the position of the shoe with sufficient accuracy they do not apply any substantial pressure to the upper. After the shoe has been presented by the operator under the holdown 8 and between the side gages 38, it is clamped against the holdown substantially at the beginning of the power operation of the machine by a shoe rest 60 which engages the top of its forepart underneath as illustrated in Fig. 7. The shoe rest 60 is supported on a lever arm 62 which is fast on a rockshaft 64 mounted in bearings in the frame. The means for operating the arm 62 to apply the shoe rest to the shoe will be hereinafter described.

For wiping the margin of the upper inwardly over the insole along the opposite sides of the forepart of the shoe, the machine is provided, like that shown in the last mentioned Letters Patent, with a pair of wipers 66 consisting of comparatively thin steel plates which are resiliently flexible in directions heightwise of the shoe to permit them to conform to the contour of the bottom of the shoe. These plates are secured, each by a pair of bolts 68, to forwardly extending arms 70 of bell-crank levers 72 pivotally mounted on studs 74 on the top frame plate 6 to swing about axes extending heightwise of the shoe. The bell-crank levers 72 have other arms 76 extending generally widthwise of the shoe in crossed relation to each other and connected respectively by links 78 to the opposite ends of a bar 80 which is integral with the upper ends of arms 82 of two other bell-crank levers 84 mounted to swing about a rod 86 on the frame, the levers 84 being further joined together by a hub 88 on the rod. The links 78 extend through openings in the bar 80 which are large enough to provide for the necessary play, and they are provided with nuts 90 and 92 arranged to engage the bar respectively on its front and rear sides. The bell-crank levers 84 are further provided with forwardly extending arms 94 which are connected near their front ends by a pair of downwardly extending links 96 to a piston 98 movable vertically in a cylinder 100 formed as part of the column 2, the piston being operated as herein-after described. The links extend downwardly within the cylinder and are connected to the

piston 98 by a pin 102, the upper end portion of the piston being provided on its opposite sides with recesses to receive the links. In response to upward movement of the piston, therefore, wiper-operating movements are imparted through the bodily movable links 96 and the bell-crank levers 84 to the bell-crank levers 72, the wiper-carrying arms 70 of the latter being swung inwardly toward each other. Such wiper-operating movements of the arms 70 are limited by their engagement with shoulders 104 formed on caps 106 which are secured to the top frame plate 6. Return movements of the arms to withdraw the wipers 66 from over the shoe are effected by springs 108 connected to the forwardly extending arms 94 of the bell-crank levers 84 and to the frame of the machine, these movements of the arms 70 being limited by their engagement with shoulders 110 on the caps 106. The caps serve also to prevent the wiper-carrying arms from being sprung upwardly by the upward pressure of the shoe on the wipers. The wipers are maintained in a heated condition, as is preferable in lasting with cement, by electrical heating units 112 mounted in blocks 114 which are secured to the lower faces of the wipers in locations such as to provide for clearance at all times between them and the side gages 38. The heating units are supplied with current from a suitable source through flexible conduits 116 attached to the blocks 114. The studs 74 about which the wipers are swung are so located that the portions of the wipers which act on the margin of the upper have components of movement lengthwise of the shoe toward its toe end, which is desirable in view of the inward curvature of the edge of the shoe bottom heelwardly of the ball line. Since shoes on which the machine operates may sometimes have therein upstanding pulling-over tacks at the sides of the toe, the wipers are provided with recesses 118 to clear such tacks.

In the machine herein shown the upward movement of the piston 98 is further utilized to impart upward swinging movement to the arm 62 and thereby to apply the shoe rest 60 in clamping and supporting engagement with the shoe. For this purpose the two bodily movable links 96, through which the wiper-operating bell-crank levers 84 are operated as hereinbefore described, are provided with forward and rearward cam projections 120 (Figs. 1 and 3) arranged to control two bell-crank levers 122 mounted to swing about rods 124 on the frame. One arm 126 of each of these bell-crank levers carries two rolls 128 normally engaged by inclined cam faces 130 on the projections 120. The other arm 132 of the front bell-crank lever is connected by a pair of links 134 to a pin 136 mounted in the lower end of an inverted U-shaped member 138 to which is secured an upwardly extending rod 140. The other arm 132 of the rear bell-crank lever is similarly connected by a single link 142 to the pin 136. Surrounding the rod 140, between the member 138 and a member 144 confined on the upper end of the rod by nuts 146, is a compression spring 148. The member 144 has a pair of upwardly extending arms 150 pivotally connected to the front end of the arm 62. At the very beginning of the upward movement of the piston 98, therefore, the inclined cam faces 130 act on the rolls 128 to swing the bell-crank levers 122 in the directions to lift the U-shaped member 138, and this member acts through the spring 148 and the member 144 to impart upward swinging movement to the arm 62 and thereby to apply

the shoe rest 60 to the shoe. After the shoe rest has arrived in shoe-clamping position the spring 148 is compressed by further movements of the bell-crank levers to hold the shoe rest forcibly against the shoe, the rod 140 moving upwardly through the member 144. As the links 96 thereafter continue their upward movements to operate the wipers, the rolls 128 are engaged by vertical faces 152 on the projections 120 to maintain the shoe rest in shoe-supporting position, as illustrated in Fig. 2.

When a shoe is pressed upwardly against the holdown 8 by the shoe rest 60 as above described, the lever 24 which supports the holdown is held positively against movement in response to pressure of the shoe on the holdown by the latch arm 30. When the wipers 66 are over the shoe bottom it is desirable to increase their pressure on the shoe to insure that all portions of the margin of the upper on which they act will be pressed firmly down on the insole into position to be secured thereto by the cement. The need for such increase of pressure further arises from the fact that the holdown is preferably so adjusted as to provide substantial clearance initially between the wipers and the insole to assist in guarding against displacement of the margin of the insole by the inward movements of the wipers. The construction herein shown is accordingly such that when the wipers have nearly completed their inward wiping movements the latch arm 30 is swung rearwardly to release the lever 24, thus permitting the shoe rest 60 under control of the spring 148 to force the shoe farther upwardly. For this purpose there is pivotally connected to the lower end of the latch arm 30 a rod 154 extending rearwardly through an opening in the bar 80 carried by the bell-crank levers 84 and having thereon a nut 156 arranged to be engaged by the bar 80 to operate the latch arm at a time in the movements of the wipers determined by adjustment of the nut. When the lever 24 is thus released it is swung by the pressure of the shoe on the holdown against the resistance of a light spring 158 mounted between its rear end and the frame plate 6, this spring being provided for thereafter returning the lever into position to permit the latch arm 30 to be returned to its normal position by the spring 36. The spring 158 is held in proper position by a screw 160 extending downwardly within it from the lever 24. When the shoe is thus pressed upwardly against the flexible wipers they bend to conform satisfactorily to the more or less convex curvature of the bottom of the shoe, the bending of the wipers being limited and controlled by screws 162 on the arms 70 in the same manner as in the machine shown in the last mentioned Letters Patent.

Arranged to cooperate with the wipers 66 to control the upper are retarders 164 which clamp the margin of the upper in upstanding position against the edges of the wipers and also serve to press the margin of the insole down on the bottom of the last as the wipers begin to wipe the upper inwardly over the insole. Preferably, as shown, the retarders are curved lengthwise of the shoe somewhat more sharply than the edges of the wipers, so that portions of the upper which may have been previously lasted in the shank or pulled over at the sides of the toe will not prevent the retarders from being moved outwardly as far as desired at the widest portion 75 of the shoe. They are pivotally mounted on ver-

tical pins 166 supported on the inner ends of outwardly extending arms 168 and are movable about the pins to permit them to adjust themselves to the edges of the wipers. The arms 168 are pivotally mounted at their outer ends for swinging movements heightwise of the shoe on pins 170 (Fig. 3) supported on the upper ends of downwardly extending arms 172. Plungers 174 pressed upwardly by springs 176 mounted in sockets in the arms 172 engage screws 178 mounted in lugs 180 on the outer ends of the arms 168 and thus tend to swing these arms in directions to lower the retarders 164. The normal positions of the arms 168 with respect to movement about the pins 170 are determined by 15 their engagement with shoulders 182 on the arms 172. When the arms 168 are in these positions the retarders 164 extend downward slightly farther than the presser feet 10 on the holdown 8 (Fig. 1), and they are accordingly 20 lifted by the shoe against the resistance of the springs 176. This insures that the retarders will apply effective downward pressure to the margin of the insole.

The arms 172 are pivotally mounted at their lower ends for swinging movements laterally of the shoe on rods 184 (Figs. 4 and 5) each of which is supported fast in the upwardly extending arms of a U-shaped member 186 having a downwardly extending stem 188 mounted to turn in a bearing formed in a bracket 190 on the frame of the machine. Also mounted to swing about the rods 184 are the forked outer ends of arms 192 (Fig. 3) which extend inwardly toward each other and have rounded inner ends engaged by the forked front ends of the previously mentioned wiper-operating arms 94. When these arms, therefore, are swung upwardly to operate the wipers they impart upward swinging movements also to the arms 192. These movements of the arms 192 cause outward swinging movements laterally of the shoe to be imparted to the arms 172 by torsion springs 194 which surround the rods 184, one end of each spring bearing against a lug 196 (Fig. 5) on the arm 172 and the other end against a pin 198 mounted in a collar 200 fast on the rod 184. The normal positions of the arms 172 relatively to the arms 192 are adjustably determined by 30 screws 202 which are mounted in extensions 204 of the forked ends of the arms 192 and engage the outer sides of the arms 172.

The outward swinging movements of the arms 172 which result from the upward movements of the arms 192, as above described, serve to move the retarders 164 from positions near the holdown 8 (Fig. 4) outwardly over the insole toward the wipers as the wipers are being moved inwardly toward the side edges of the insole, the retarders thus having a spreading action on the margin of the upper. When the retarders and the wipers arrive in positions to clamp the upstanding margin of the upper between them the retarders preferably are so located that their upper-engaging faces at the widest portion of the shoe are positioned slightly farther outward than the side edges of the insole, as illustrated in Fig. 8, so as to detach from the edges of the insole any portion of the upper which may have adhered prematurely thereto. In order that the retarders will be properly positioned relatively to the side edges of the insole when the upper is first clamped against them by the wipers in operating on shoes of different widths, the arms 172 are adjusted relatively to the arms 192 by the screws 202 to posi-

tion the retarders initially at such distances from the edges of the insole as to insure that result. As the wipers continue their inward movements after having clamped the upstanding margin of the upper against the retarders they force the retarders inwardly against the resistance of the torsion springs 194 by the pressure applied thereto through the margin of the upper. In this manner the wipers and the retarders cooperate to apply an inward pull to the margin of the upper, thus drawing the upper tightly over the edge of the insole. Shortly after the wipers begin to wipe the margin of the upper inwardly over the insole, however, the retarders are lifted against the resistance of the springs 176 to withdraw them from the paths of the wipers. For this purpose there are mounted on the arms 168 members 208 (Figs. 4 and 8) having ears extending downwardly through slots in the arms and supporting rolls 210 which are engaged by the wiper-carrying arms 70 to swing the arms 168 upwardly about the pins 170 and thereby to lift the retarders. The members 208 are clamped on the arms 168 by screws 212 which extend through slots in the members to permit the latter to be adjusted to determine precisely the time in the inward movements of the arms 70 when the retarders are lifted. When the retarders have thus been moved upwardly far enough to clear the wipers they are moved outwardly over the wipers, as the wipers continue their inward movements, by the springs 194 acting on the arms 172. Early in such outward movements of the retarders they serve to bend the margin of the upper outwardly over the edges of the wipers, as illustrated in Fig. 10, and thus to increase the effectiveness of the wipers in wiping the upper tightly and smoothly over the insole. Outward swinging movements of the arms 172 are adjustably limited by screws 214 arranged to engage the arms and mounted in brackets 216 on the frame.

Under some conditions it may be desirable that the retarder 164 which cooperates with the wiper acting at the outer side of a right or a left shoe shall be positioned somewhat farther from the end of the toe than the other retarder. Accordingly the construction herein shown provides for relative adjustment of the retarders lengthwise of the shoe. For this purpose diametrically enlarged portions of the rods 184 extending forwardly of the arms 192 are connected together by a crossbar 218 the opposite ends of which are pivotally mounted on pins 220 on the rods, and the right-hand rod 184 is extended still farther forwardly to provide a handle 222 (Fig. 4). By means of this handle, therefore, the two rods 184 may be swung simultaneously in the same directions about the axes of the studs 188, and it will be evident that such swinging movements of the rods are accompanied by swinging movements of the arms 168 in opposite directions respectively lengthwise of the shoe to position one of the retarders nearer the end of the toe and the other farther from the end of the toe. When the retarders have thus been adjusted as required for a right or a left shoe, they will ordinarily maintain their adjusted relation without special retaining means, although such means may be provided if desired.

Upward movement of the piston 98 to operate the wipers and other parts is effected by operating fluid, preferably compressed air, admitted to the lower end of the cylinder 100 through a pipe 224. The air is thus admitted by a valve 226 controlled by a solenoid 228 which is energized by the clos-

ing of a switch 230 in response to the presentation of a shoe to the machine, the toe end of the shoe engaging a pivotally mounted starting member 232 which acts on the switch through a bell-crank lever 234. After the wipers have been moved inwardly over the shoe bottom they remain in pressure-applying relation to the margin of the upper during a short interval which is terminated by the opening of the switch 230 in response to upward movement of a piston 236 mounted in a cylinder 238 which receives compressed air through an adjustable needle valve 240. The parts of the machine then return to their starting positions. A more complete disclosure of the means for thus controlling the operation of the machine will be found in the previously mentioned application of which this application is a division.

The manner of operation of the machine, in so far as it is of interest with reference to the present invention, will now be briefly summarized. The operator presents a shoe between the side gages 38 with its insole in contact with the retarders 164 and with its toe-end face in engagement with the starting member 232 and by pressing the shoe against this member closes the switch 230 to start the machine. By upward movement of the piston 98 operative movements are then imparted to the wiper-operating bell-crank levers 84. At the beginning of the upward movement of the piston the two bell-crank levers 122 are operated by the cam faces 130 on the projections 120 of the links 96 to move the shoe rest 60 upwardly into position to clamp the shoe against the presser feet 10 of the holdown 8, the spring 148 being compressed to maintain the shoe rest in clamping position. This action of the shoe rest on the shoe causes the latter to raise the retarders 164 slightly until the insole engages the presser feet 10. As the piston 98 continues its upward movement to operate the wipers the rolls 128 of the bell-crank levers 122 rest against the vertical faces 152 of the projections 120, as shown in Fig. 2. Simultaneously with the inward movements of the wipers the arms 192 are swung upwardly to cause the springs 194 to impart outward swinging movements to the arms 172 and thereby to move the retarders 164 outwardly over the insole toward the incoming wipers. The retarders thus serve to spread portions of the margin of the upper outwardly from over the insole, and when they arrive in positions where their upper-engaging faces at the widest portion of the shoe are positioned slightly farther outward than the side edges of the insole, as illustrated in Fig. 8, the wipers arrive in positions to clamp the upstanding margin of the upper against them. As the wipers thereafter continue their inward movements they force the retarders inwardly against the resistance of the springs 194, and in this operation the wipers and the retarders serve to apply an inward pull to the margin of the upper over the extreme edge of the insole, as illustrated in Fig. 9, the retarders at the same time pressing the margin of the insole down on the last to prevent it from being displaced by the wipers. Substantially at the time in the operation of the machine indicated by Fig. 9 the wiper-carrying arms 70 arrive in positions to engage the rolls 210, and by their further movements they act on these rolls to swing the arms 168 upwardly against the resistance of the springs 176 and thereby to lift the retarders 164. When the retarders have thus been lifted far enough they are moved outwardly

over the wipers by the action of the springs 194, and early in such outward movements they serve to bend the margin of the upper outwardly over the edges of the wipers, as illustrated in Fig. 10, thus increasing the effectiveness of the wipers in wiping the margin of the upper tightly inward over the insole. In completing their inward movements the wipers wipe the margin of the upper throughout its width into parallel relation to the insole, as shown in Fig. 11. Shortly before the wiper-carrying arms 70 arrive in the positions determined by their engagement with the shoulders 104, the bar 80 of the bell-crank levers 84 acts on the nut 156 to swing the latch arm 88 rearwardly and thus to release the holdown 8. The spring 148 controlling the shoe rest 60 then serves to force the shoe farther upwardly against the wipers to increase their pressure on the margin of the upper and to cause them to bend into better conformity to the contour of the shoe bottom. The wipers having completed their inward movements, they remain in pressure-applying relation to the margin of the upper until the piston 236 has been raised far enough by the compressed air admitted beneath it through the needle valve 240 to cause the switch 230 to open. When the circuit through the solenoid 228 is thus broken the valve 226 is returned to its initial position and the air is released from the cylinders 100 and 230. The parts are then returned to their initial positions, the wipers being withdrawn from over the shoe by the action of the springs 194 on the bell-crank levers 84, and the shoe is released to permit the operator to remove it.

Having described the invention, what I claim as new and desire to secure by Letters Patent of the United States is:

1. In a lasting machine, overlaying members movable to lay the margin of an upper inwardly over an insole on a last at the opposite sides of the last respectively, lever mechanism movable to operate said members, retarders movable outwardly over the insole in response to the movement of said lever mechanism for clamping the margin of the upper against said overlaying members to control it in the lasting operation, a shoe rest movable heightwise of the shoe into position to support the shoe at the top of the forepart during the operation of said overlaying members and retarders on the upper, controlling mechanism connected to said shoe rest, means bodily movable to operate said lever mechanism, and cam means carried by said bodily movable means for operating said controlling mechanism to move the shoe rest into shoe-supporting position in predetermined time relation to the movements of the overlaying members and retarders.

2. In a lasting machine, overlaying members movable to lay the margin of an upper inwardly over an insole on a last at the opposite sides of the last respectively, arms mounted for swinging movements heightwise of the last and connected to said members for operating them, retarders movable outwardly over the insole in response to the swinging movements of said arms for clamping the margin of the upper against said overlaying members to control it in the lasting operation, a shoe rest movable heightwise of the shoe into position to support the shoe at the top of the forepart during the operation of said overlaying members and retarders on the upper, controlling mechanism connected to said shoe rest, means bodily movable to swing said arms, and cam means carried by said bodily movable means

for operating said controlling mechanism to move the shoe rest into shoe-supporting position in predetermined time relation to the movements of the overlaying members and retarders.

3. In a lasting machine, overlaying members movable to lay the margin of an upper inwardly over an insole on a last at the opposite sides of the last respectively, lever mechanism movable to operate said members, retarders movable outwardly over the insole in response to the movement of said lever mechanism for clamping the margin of the upper against said overlaying members to control it in the lasting operation, a shoe rest movable heightwise of the shoe into position to support the shoe at the top of the forepart during the operation of said overlaying members and retarders on the upper, controlling mechanism connected to said shoe rest, a fluid-operated member, a link connection between said fluid-operated member and said lever mechanism for operating that mechanism, and means carried by said link connection for operating said controlling mechanism to move the shoe rest into shoe-supporting position in predetermined time relation to the movements of the overlaying members and retarders.

4. In a lasting machine, lasting means movable to lay the margin of an upper inwardly over an insole on a last, a member for positioning the shoe heightwise relatively to said lasting means, a shoe rest movable to clamp the shoe against said member, an operating member, mechanism connecting said operating member to the lasting means to operate the latter, said mechanism including a bodily movable link connection, cam means carried by said bodily movable link connection, and additional mechanism arranged to be operated by said cam means to move said shoe rest into clamping position in predetermined time relation to the operation of the lasting means.

5. In a lasting machine, lasting means movable to lay the margin of an upper inwardly over an insole on a last, a member for positioning the shoe heightwise relatively to said lasting means, a shoe rest movable to clamp the shoe against said member, lever mechanism connected to the lasting means for operating the latter, a fluid-operated member, a link connection between said fluid-operated member and the lever mechanism for operating that mechanism, cam means carried by said link connection, and additional mechanism arranged to be operated by said cam means to move said shoe rest into clamping position.

6. In a lasting machine, lasting means movable to lay the margin of an upper inwardly over an insole on a last, a member for positioning the shoe heightwise relatively to said lasting means, a shoe rest movable to clamp the shoe against said member, a fluid-operated piston, mechanism connecting said piston to the lasting means to operate the latter, said mechanism including a member movable bodily in the same general direction as the piston, additional mechanism yieldingly connected to said shoe rest for moving it into clamping position, and cam means carried by said last-named member for operating said additional mechanism and for holding the latter thereafter stationary during continued movement of the piston.

7. In a lasting machine, overlaying members movable to lay the margin of an upper inwardly over an insole on a last at the opposite sides of the last respectively, retarders for clamping the margin of the upper against said overlaying members to control it in the overlaying operation, arms

connected to said retarders and mounted for swinging movements in locations opposite the sides of the shoe about axes extending lengthwise of the shoe to move the retarders outwardly over the insole into positions to clamp the margin of the upper against the overlaying members, lever mechanism movable to operate the overlaying members, and means controlled by said lever mechanism for thus swinging said arms as the overlaying members are operated.

8. In a lasting machine, overlaying members movable to lay the margin of an upper inwardly over an insole on a last at the opposite sides of the last respectively, arms mounted for swinging movements heightwise of the shoe and connected to said overlaying members for operating them, retarders for clamping the margin of the upper against said overlaying members to control it in the overlaying operation, arms connected to said retarders and mounted for swinging movements in locations opposite the sides of the shoe about axes extending lengthwise of the shoe to move the retarders outwardly over the insole into positions to clamp the margin of the upper against the overlaying members, and means for thus swinging said last-named arms in response to the movements of said first-named arms.

9. In a lasting machine, overlaying members movable to lay the margin of an upper inwardly over an insole on a last at the opposite sides of the last respectively, arms mounted for swinging movements heightwise of the shoe and connected to said overlaying members for operating them, retarders for clamping the margin of the upper against said overlaying members to control it in the overlaying operation, arms connected to said retarders and mounted for swinging movements in locations opposite the sides of the shoe about axes extending lengthwise of the shoe to move the retarders outwardly over the insole into positions to clamp the margin of the upper against the overlaying members, and springs for thus swinging said last-named arms in response to the movements of said first-named arms, said springs being yieldable to permit the retarders to be moved inwardly over the insole by the overlaying members.

10. In a lasting machine, overlaying members movable to lay the margin of an upper inwardly over an insole on a last at the opposite sides of the last respectively, retarders for clamping the margin of the upper against said overlaying members to control it in the overlaying operation, arms supporting said retarders and arranged to extend outwardly therefrom widthwise of the shoe, and other arms supporting said first-named arms at the outer ends of the latter and mounted for swinging movements widthwise of the shoe about different axes extending lengthwise of the shoe to move the retarders outwardly over the insole toward the overlaying members into positions to clamp the margin of the upper against said members.

11. In a lasting machine, overlaying members movable to lay the margin of an upper inwardly over an insole on a last at the opposite sides of the last respectively, retarders for clamping the margin of the upper against said overlaying members to control it in the overlaying operation, arms supporting said retarders and arranged to extend outwardly therefrom widthwise of the shoe, other arms supporting said first-named arms at the outer ends of the latter and mounted for swinging movements widthwise of the shoe about different axes extending lengthwise of the

shoe, and spring means arranged to control said other arms and against the resistance of which they are thus movable in response to pressure of the overlaying members on the retarders to permit the retarders to be moved inwardly over the insole in the overlaying operation.

12. In a lasting machine, overlaying members movable to lay the margin of an upper inwardly over an insole on a last at the opposite sides of the last respectively, retarders for clamping the margin of the upper against said overlaying members to control it in the overlaying operation, arms supporting said retarders and arranged to extend outwardly therefrom widthwise of the shoe, other arms supporting said first-named arms at the outer ends of the latter and mounted for swinging movements widthwise of the shoe about different axes extending lengthwise of the shoe to move the retarders outwardly over the insole toward the overlaying members, said first-named arms being mounted on said other arms for swinging movements heightwise of the shoe, and spring means tending thus to swing said first-named arms in one direction and thereby to press the retarders on the insole as they are moved outwardly over the insole.

13. In a lasting machine, overlaying members movable to lay the margin of an upper inwardly over an insole on a last at the opposite sides of the last respectively, retarders for clamping the margin of the upper against said overlaying members to control it in the overlaying operation, arms supporting said retarders and arranged to extend outwardly therefrom widthwise of the shoe, other arms supporting said first-named arms and mounted for swinging movements in locations opposite the sides of the shoe each about an axis extending lengthwise of the shoe, lever mechanism movable to operate said overlaying members, and means for swinging said other arms widthwise of the shoe in response to the movement of said lever mechanism to move the retarders outwardly over the insole into positions to clamp the margin of the upper against the overlaying members.

14. In a lasting machine, overlaying members movable to lay the margin of an upper inwardly over an insole on a last at the opposite sides of the last respectively, retarders for clamping the margin of the upper against said overlaying members to control it in the overlaying operation, arms supporting said retarders and arranged to extend outwardly therefrom widthwise of the shoe, other arms supporting said first-named arms and mounted for swinging movements in locations opposite the sides of the shoe each about an axis extending lengthwise of the shoe, lever mechanism movable to operate said overlaying members, and spring means controlled by said lever mechanism for swinging said other arms to move the retarders outwardly over the insole into positions to clamp the margin of the upper against the overlaying members, said spring means being thereafter yieldable in response to pressure of the overlaying members on the retarders to permit the retarders to be moved inwardly over the insole in the overlaying operation.

15. In a lasting machine, overlaying members movable to lay the margin of an upper inwardly over an insole on a last at the opposite sides of the last respectively, retarders for clamping the margin of the upper against said overlaying members to control it in the overlaying operation, arms supporting said retarders and arranged to

extend outwardly therefrom widthwise of the shoe, and other arms supporting said first-named arms and arranged to extend heightwise of the shoe in locations opposite the sides of the shoe, said other arms being mounted for swinging movements widthwise of the shoe each about an axis extending lengthwise of the shoe to move the retarders outwardly over the insole toward the overlaying members into positions to clamp the margin of the upper against said members.

16. In a lasting machine, overlaying members movable to lay the margin of an upper inwardly over an insole on a last at the opposite sides of the last respectively, retarders for clamping the margin of the upper against said overlaying members to control it in the overlaying operation, arms supporting said retarders and arranged to extend outwardly therefrom widthwise of the shoe, other arms supporting said first-named arms and arranged to extend heightwise of the shoe in locations opposite the sides of the shoe, said other arms being mounted for swinging movements widthwise of the shoe each about an axis extending lengthwise of the shoe, and spring means arranged to control said other arms and against the resistance of which they are thus movable in response to pressure of the overlaying members on the retarders to permit the retarders to be moved inwardly over the insole in the overlaying operation.

17. In a lasting machine, overlaying members movable to lay the margin of an upper inwardly over an insole on a last at the opposite sides of the last respectively, retarders for clamping the margin of the upper against said overlaying members to control it in the overlaying operation, and mechanism including a member common to both said retarders for adjusting them in opposite directions respectively lengthwise of the last.

18. In a lasting machine, overlaying members movable to lay the margin of an upper inwardly over an insole on a last at the opposite sides of the last respectively, retarders for clamping the margin of the upper against said overlaying members to control it in the overlaying operation, arms supporting said retarders and arranged to extend outwardly therefrom widthwise of the shoe, other arms supporting said first-named arms and arranged to extend heightwise of the shoe, and means for adjusting said retarders simultaneously in opposite directions respectively lengthwise of the shoe by movements of said other arms about axes extending heightwise of the shoe.

19. In a lasting machine, overlaying members movable to lay the margin of an upper inwardly over an insole on a last at the opposite sides of the last respectively, retarders for clamping the margin of the upper against said overlaying members to control it in the overlaying operation, arms supporting said retarders and arranged to extend outwardly therefrom widthwise of the shoe, other arms supporting said first-named arms at the outer ends of the latter and arranged to extend heightwise of the shoe, said other arms being mounted to turn about axes extending heightwise of the shoe to adjust the retarders lengthwise of the shoe, and a link connection between said other arms constraining them to turn simultaneously in such directions as to adjust the retarders respectively in opposite directions lengthwise of the shoe.
